FISHING LURE SIMULATING A SQUID

Millard F. Rose, Jr., Aloha, Oreg., assignor of a fractional part interest to Ruby F. Williams, Depoe Bay, Oreg.

Filed Dec. 7, 1973, Ser. No. 422,740

Term of patent 14 years

Int. Cl. D22—05

U.S. Cl. D22—27

FIG. 1 is a front elevational view of the fishing lure simulating a squid,

FIG. 2 is a side elevational view of the lure,

FIGS. 3 and 4 are sectional views taken downwardly along horizontal lines 3 and 4 respectively of FIG. 2 with the fishhooks removed from the lure.

FIG. 5 is a bottom plan view of the lure as shown in FIG. 1, and

FIG. 6 is a top plan view of the lure as shown in FIG. 2.

I claim:

The ornamental design for a fishing lure simulating a squid, as shown.
